(57) **CLAIM**

We claim the ornamental design for a long shaft propeller controller, as shown and described.

DESCRIPTION

FIG. 1 is a top plan view showing our new design;
FIG. 2 is a bottom plan view thereof;
FIG. 3 is a right side elevation view thereof;
FIG. 4 is a left side elevation view thereof;
FIG. 5 is a rear elevation view thereof;
FIG. 6 is a front elevation view thereof; and,
FIG. 7 is a top, front perspective view thereof, showing the environmental structure of a long shaft propeller, depicted by means of broken lines, which forms no part of the claimed design.

1 Claim, 4 Drawing Sheets
